UNITED STATES PATENT OFFICE.

AXEL F. LARSON AND KARL O. OSTERGREN, OF CHICAGO, ILLINOIS, ASSIGNEES TO MARQUETTE PIANO COMPANY, OF CRYSTAL FALLS, MICHIGAN, A CORPORATION OF MICHIGAN.

AUTOMATIC PLAYING-PIANO.

No. 891,938.

Specification of Letters Patent.

Patented June 30, 1908.

Application filed February 24, 1906. Serial No. 302,765.

To all whom it may concern:

Be it known that we, AXEL F. LARSON and KARL O. OSTERGREN, citizens of the United States, residing at Chicago, in the county of Cook and State of Illinois, have invented a certain new and useful Improvement in Automatic Playing-Pianos, of which the following is a full, clear, concise, and exact description, reference being had to the accompanying drawings, forming a part of this specification.

Our invention relates to automatic playing pianos, and its object is to provide for association with a piano of ordinary design playing mechanism so constructed and so arranged that it may easily be mounted within a piano case of ordinary size and design and so disposed with reference to the striking mechanism of the instrument that it may operate the different hammers and their associated mechanism according to the form of the note sheet which is employed to govern the playing mechanism.

It is one of the important features of our invention that the construction of the piano itself need be in no way altered in order to associate therewith the playing mechanism herein described and shown.

It is further an important feature of our invention that the parts which are necessarily accessible to the operator for manipulating the playing mechanism may be readily hidden from view when the piano is to be operated in the usual manual way, there being practically no difference in the outside appearance of a playing piano such as herein disclosed when the playing mechanism is not in use, and a piano of ordinary construction.

It is a primary object of this invention to provide a construction which can be easily repaired and adjusted, and which does not easily get out of order.

The various improvements will hereinafter be more fully pointed out and will be made more clear by reference to the accompanying drawings in which

Figure 1 is a front elevation of the piano, the front boards of the case being removed so as to disclose the construction of the parts within the same. Fig. 2 is a cross-sectional view taken on the line 2, 2 of Fig. 1. Fig. 3 is a cross-sectional view of the playing mechanism taken on line 3, 3 of Fig. 1. Fig. 4 is a sectional view taken on the line 4, 4 of

Fig. 3, parts being broken away so as to more clearly illustrate the disposition of the various parts. Fig. 5 is a rear view of the action or playing mechanism. Fig. 6 is a sectional view taken on the line 6, 6 of Fig. 1. Fig. 7 is a sectional view taken on the line 7, 7 of Fig. 1. Fig. 8 is a rear view of the bellows board and the exhaust feeders employed. Fig. 9 is a top view of the construction shown in Fig. 8, the cover being removed so as to disclose the parts within. Fig. 10 is a section on the line 10, 10 of Fig. 9. Fig. 11 is a section on the line 11, 11 of Fig. 9. Fig. 12 is a section on the line 12, 12 of Fig. 9. Fig. 13 is a bottom view of the piano, parts being broken away to more clearly illustrate the construction. Fig. 14 is a sectional view on the line 14, 14 of Fig. 1. Figs. 15 and 16 are views of the treadle mechanism which will be hereinafter described. Fig. 17 is a partial front view of the piano, parts being broken away to disclose the pedal mechanism. Fig. 18 is a detail view which will be hereinafter described. Fig. 19 is a sectional view taken on the line 19, 19 of Fig. 1. Fig. 20 is a partial sectional view taken on the line 20, 20 of Fig. 2. Fig. 21 is a detail view which will be hereinafter described. Fig. 22 is an isolated view showing the means employed for holding the piano keys while the automatic playing mechanism is in use. Fig. 23 is a detail view showing the construction employed for regulating the position of the note sheet. Fig. 24 is a detail view which will be hereinafter described. Fig. 25 shows a modification which may be employed and which will be hereinafter described. Fig. 26 shows an end view of the playing mechanism when the modification shown in Fig. 25 is employed. Fig. 27 is a perspective view of a piano embodying our invention when the playing mechanism is not in use.

Upon the supporting wall, 1, of the piano is firmly mounted the action, 2, by means of the screws, 2', the passage ways, 3, 3, in the end blocks, 4, 4, registering with the openings or passages, 5, 5, in the supporting wall 1. A piece of felt or similar material may be clamped between the block 4 and supporting wall 1 so as to insure air tight connection, and we employ this means wherever it may be used throughout the entire construction. Upon the under side of the supporting wall 1 is securely mounted the air chest, 6, which

communicates with the action above the supporting wall by way of openings 7 in the cover 7' thereof, registering with the passage ways 5, 5 in the supporting or foundation wall 1. The air chest 6 is associated with the various bellows which will be hereinafter described.

Upon the rear side of a supporting board, 8, are mounted the feeders 9 and 10. The feeders are each provided with the exhaust valve, 9', and the suction valve, 9''. These valves are formed by a leather strip placed over the ports, securely fastened at one end and held taut by means of a spring, 10', bearing against a block 11', glued to the leather strip. The function of these valves is, of course, evident from the drawings. Each feeder is provided with an extension, 11, which is provided with a bifurcated end, 12, in which is pivoted the link, 13, the other end of which is pivoted to the arm, 14 of the bell crank lever 15. The other arm, 16, thereof may be brought into and out of use and forms a part of bell crank lever, 15, only when it is engaged by the support, 17. When this arm, 16, is not in use it may be swung about the pivot, 18, and brought into engagement with the spring, 19, where it may be held until it is desired to be brought into use. The power bellows 9 and 10 are held normally collapsed by a spring, 20, fastened to the block, 21, in the piano frame.

Treadles, 22, 22, are pivoted at 23 to the frame, 24, which is loosely mounted in the slides, 25, fastened to the bottom board of the piano. To the treadles are permanently pivoted the connecting rods, 26, 26, and the connecting rods 26 are provided with heads, 27, 27, which are so constructed that a temporary connection may be had between the pivot, 28, therein and the notch, 29, in the lever arm, 16. When this connection is made, that is, when the parts are so disposed as shown in Fig. 14, the treadles are in position to operate the feeders 9 and 10. When the treadles are forced downwards the power bellows are distended against the tension of the spring, 20, which causes the collapse of the power bellows when the treadles are relieved of the downward force.

When the treadles are not in use the lever arm 16 may be removed from engagement with the pivot 28 and the connecting rods 26, 26 and the treadles 22, 22 may be lowered to the frame 24 and the entire device may be inserted in the slides under the piano. In order that the frame 24 may set firm when the treadles are in use, we provide locking means which is plainly shown in Fig. 16. The rear end of the frame 24 is provided with the strip, 30, which, when drawn forward, comes into engagement with the block, 31, fastened to the under side of the piano. When the frame is in the slides the lower side of the frame engages the wood strip, 31', which is

fastened to the members, 32, 32, by means of the metal strip, 33, 33. This insures noiseless action. The front end of the metal strip 33 is beveled, as is clearly shown in Fig. 16, and the parts of the treadle frame are so disposed that when the side piece, 34, of the frame 24 drops out of engagement with the wood strip 31' the front piece, 35, thereof will engage the floor and the strip 30 will engage the block 31, as clearly shown in Fig. 16. This action brings the edge, 35', into close engagement with the beveled edge, 36, of the metal strip 33, and thus the frame is securely locked in position. When it is desired to return the treadles to their hidden position the frame is raised out of engagement with strip 35 and it may once more slide upon the wood strip 31'. It is thus seen that with this construction the pedal mechanism may easily be placed out of view when not in use, the treadles and connecting rods and frame being placed, as just described, under the piano while the lever arms 16 of the bell crank levers may be swung back and held out of sight until it is desired to bring them into use.

In order that an instrument of good appearance may be had when the treadle mechanism is not in use, we construct the front panel, 37, as shown in detail in Fig. 24. The panel is composed of the stationary portions, 38, 38, 38, and the sliding portions, 39, 39, which, as is evident from the drawing, may be moved aside into the position shown in dotted lines in Fig. 24. This leaves the openings, 40, 40, through which the lever arms 16 may be drawn and brought into use. When the treadle mechanism is not in use the passages may be closed and the panel will appear as shown in Fig. 27.

The playing mechanism is operated entirely by suction, this suction being created by the operation of the feeders 9 and 10, as clearly shown in Figs. 8 and 9, the feeders connecting with the chamber, 41, of the chest 6 by way of the passages 41' and 42. Upon the front side of the supporting board, 8, is mounted the main bellows, 43, which connects with the chamber 41 by way of the passage way, 44; this passage being opened and closed by means of the valve, 45. The bellows 43 is provided with the safety valve, 43'. The valve is held normally open by means of the helical spring, 46. It is evident since the air regulating chamber 41 is air tight that normally the air will be exhausted from the main bellows 43 when the power bellows are operated. This causes the collapse of the bellows against the tension of the springs, 44', 44'. These springs create a steady distension of the bellows 43 which consequently causes a steady exhaust of the air in the chamber 41; that is, the bellows 43 acts as a reservoir. The chamber 41 is connected with the chamber 46' by way of the 180

passage way, 47, which is opened and closed by means of the valve, 48, normally held open by means of the spring, 49. The chamber 46 communicates with the passageways 3, 3 in the end blocks of the action, by way of the openings 7, 7 in the cover 7' and the openings 5, 5 in the foundation wall 1.

Referring now more particularly to Fig. 3, it will be seen that the passage ways 3, 3 connect directly to the action chamber, 50. It is now apparent that the operation of the feeders 9 and 10 will create a partial vacuum in the air chambers 41 and 48' in the channels 3, 3 and in the action chamber 50. Se- 15 curely mounted in the box, 51, is the tracker-board, 52, over which a note sheet, 53, provided with the usual openings may pass from its spool, 54, to the roller, 55. This construction is well known to those skilled in 20 the art and needs no explanation here. The tracker-board is provided with the usual openings, 53', which connect by way of the tubes, 54', 54', with the channels, 55', 55', in the channel strip, 56. Each of these chan- 25 nels 55' connect with a primary pneumatic, 57, which is composed of the chamber, 58, and the flexible leather diaphragm, 59. A valve, 60, is mounted upon the valve stem, 61, secured by means of the nut, 62, to the 30 pneumatic diaphragm, 59, the movement of said valve stem being guided by the cross-strip, 63. The valve 60 is so disposed that when the pneumatic diaphragm is in its normal position; that is, its lowered position, it 35 closes the passage way between the action chamber 50 and the channel, 64. It is understood, of course, that there is a plurality of these channels in the channel board, 65, a channel leading from each valve to an action 40 bellows, 66. The action chamber 50 communicates with the channel 55' by way of a small passage way, 67, the size of which may be regulated by the screw, 68. It is now evident that when the air is exhausted from the 45 regulating chambers and from the action chambers a partial vacuum will also be formed in the primary pneumatic chamber 58 and in the channels connected therewith, the air being exhausted through the small 50 passage way 67.

When an opening in the note sheet registers with an opening in the tracker-board the outside atmosphere is admitted through a tube, 54', and through the channel, 55', to the primary pneumatic chamber 58. This sudden rush of air into these channels increases the pressure on the lower side of the pneumatic diaphragm 59, causing it to be much greater than that in the action chamber 50, the passage way 67 being of so small a size that practically no air will pass therethrough into the action chamber when the channels 54', 55' and the chamber 58 are suddenly flooded with the outside atmosphere. 65 This great difference in pressure between that

in the action chamber 50 and that in the primary pneumatic chamber 58 causes the diaphragm 59 to be rapidly raised, the valve 60 being carried therewith. This, of course, opens the passage between the channel 64 70 and the action chamber and almost simultaneously closes the port, 69, to the outside atmosphere. It will thus be seen that a passage way is effected between the action chamber 50 and the actively associated ac- 75 tion bellows 66. The air, therefore, is exhausted from the action bellows 66, which, of course, causes the collapse thereof.

The movable element of the action bellows is provided with the extension 70, to which is 80 secured by means of the nut, 71, the rod, 72, which is mounted in the guide strip, 72', and is provided at its upper end with the button, 73. The action bellows being in a series of horizontal rows, may be staggered so as to 85 obtain the proper distribution of the buttons, 73. It is now evident that the collapse of an action bellows will raise the associated button 73 a predetermined distance.

Referring now more particularly to Fig. 2, it will be seen that the button 73 is associated with the adjustable head, 74, on the wippen, 75, of the piano action; the wippen, 75, being pivoted at 76. It will be seen that the raising of the button 73 will actuate the wippen 75 in precisely the same manner and with precisely the same effect as would the action of the associated key. As is shown in Fig. 2, the key, 77, effects this raising of the wippen 75 by means of the connecting rod, 78. This 100 actuation of the wippen 75 of course actuates the hammer and damping mechanism as is common to all piano constructions, and it is an important feature of my invention that this wippen 76 need be in no way altered or reconstructed except to add the adjustable head 74 in order that the plurality of buttons 73, 73 may be brought into association therewith, their operation effecting the operation of the piano action with precisely the same effect as it would were the keys themselves actuated manually. In Fig. 22 we have illustrated a means whereby the keys are held fast during the operation of the piano action by the automatic playing mechanism. 110

We provide a rail, 77', for engagement with the underside of the keys 77 which rides in the guides, 78', 78''. A stop, 78''' limits its motion. Upon the under side of this rail we provide the triangular lugs, 79', 79'', which are adapted to engage the adjustable blocks 80', 80''. The rail 77' is also provided with an extension or handle, 81', which extends through the slot, 82', in the key bed and in the wall 1, so that it may be easily reached. It is evident that the rail 77' can be moved from right to left, or vice versa. Normally the rail is in its left-hand position out of engagement with the keys. When it is desired to bind the keys so that they will not be op- 130

erated while the piano action is operated automatically the rail is moved toward the right and is consequently raised by reason of the engagement of the edge, 83, with the edge, 84, of the adjustable block. When the rail is in its extreme right-hand position the lugs, 79', rest upon the top of the block, 80'. We prefer making this adjustable block of such a construction as that shown in Fig. 22. It is evident that it may be adjusted by the manipulation of the screws, 85', 85", which causes the block to rock on the fulcrum, 86', in either direction until the desired position has been attained.

In order that the touch of the instrument may be stronger in order to secure louder sound, we provide the auxiliary bellows, 79, mounted upon the foundation board 8 and connecting with the air chamber 41 by means of the opening, 80. This opening is regulated by the valve, 81, normally held so as to close the opening 80 by means of the spring, 82. The bellows 79 creates a greater suctional force than bellows 43 on account of its smaller area and when it is desired to use this increased suctional force a lever mechanism presently to be described may be brought into use whereby the valve 45 is closed and the valve 81 is opened. This operation disconnects the main bellows and brings into use the auxiliary bellows. In order to secure this alternative opening and closing of the valves 45 and 81, we provide the shaft, 83, mounted in the blocks, 84, 84, and provided with the cranks, 85, 86 and 87. Mounted in the side wall, 88, and the dividing wall, 89, of the air chest is the rod, 90, provided at its end with the crank, 91, composed in part of the wooden block, 92.

It is evident that when the rod, 90, is turned in the proper direction the block, 92, will engage the crank 85 and will thereby force the same downward turning the shaft 83 so as to lower the crank 87 and raise the crank 86. The crank 87 engages, as is clearly shown in Fig. 10, the pin, 93, on the valve 45, and it is evident therefrom that the valve may be closed when the crank 87 is turned in the direction of the arrow, 94, against the tension of the spring 46. The crank 86 engages, as is clearly shown in Figs. 11 and 12, the pin 95 in the valve 81 and it is evident from the drawings that when the shaft 83 is turned about in the direction of the arrow, 94, the valve 81 will be opened against the tension of the spring 82. In order to secure this proper rotation of the shaft 90, we provide a construction which is clearly illustrated in Figs. 13 and 17. This rod or shaft 90 extends to the front of the piano and is mounted in the blocks, 96, 96, and is provided at the front end with the crank, 97, extending in practically the same direction as the crank 91. Mounted in the wall 1 is the push button, 98, which connects with the

crank 97 by way of the rod 99. It is now apparent that the shaft 90 may be rotated so as to cause the proper rotation of the shaft 83 by pressing the button 98 downwardly. This operation causes the desired rotation of the shaft 90 against the combined tension of the springs 46 and 82.

In Figs. 13, 17 and 18 we have shown a construction for association with the usual pedal mechanism of pianos whereby the operation usually secured by the pedal mechanisms in pianos of ordinary construction may be obtained by hand. In Fig. 17 we have shown the pedal levers, 100 and 101, and the pedals, 102, 102, associated therewith at one end and the connecting rods, 103 and 104, associated with the levers 100 and 101 respectively on their other ends. The rod 103 connects with the piano hammer rest rail, 105, the operation of the associated pedal bringing the hammers, 106, up close to the piano strings, as is usual in pianos of ordinary construction, while the connecting rod, 104, connects with the forte damper rod, 107, in such a manner that the operation of the associated pedal mechanism will move the dampers from the strings, as is usual in pianos of ordinary construction. The rod, 103, is provided with the pin, 108, the stem of which rides in the slot, 109 in the link, 110. This link is pivoted at 111 to the crank arm, 112, of the shaft, 113, which is mounted in the block, 114. At the front end the shaft, 113, is provided the lever arm, 114', which extends upwardly through a slot, 115, in the foundation wall 1. A connecting rod, 116, is pivoted at 117 to this lever arm, the connecting rod 116 being mounted in bearings, 118, 118, and provided with the finger piece, 119, at its other end. This finger piece extends through the slot, 120, in the key strip, 121, where it may be manipulated by the operator of the instrument. The connecting rod 104 is provided with a link similar to the link 110 which is pivoted to a crank on the shaft, 122, the same being mounted in the block, 123, fastened to the under side of the foundation wall 1. The shaft 122 is provided with the lever arm, 124, which extends upwardly through slot, 115, and to which is pivoted at 125 the connecting rod 126 which rides in the bearings, 118, 118, and which is provided at its other end with the finger piece, 127, which extends through the slot, 128, in the key strip 121, where it may be manipulated. We find it convenient to have the cranks 112 extend from their respective shafts in opposite directions so that the finger pieces 119 and 127 may both be moved toward the partition, 129, between the slots 120 and 128 when either the frame 105 or the rod 107 are to be operated. It will be apparent from Fig. 17 and Fig. 1 that the finger pieces 119 and 127 and the button 98 are so situated with reference to each other that

the three parts may be operated simultaneously or one at a time with one hand, the effect of the operation of the finger pieces 119 and 127 being precisely the same as that obtained by the employment of the pedals, 102, 102. It is manifest, of course, that by reason of the pin and slot connection between the link 110 and the rod 103 the operation of the pedals 102, 102, when the instrument is used as an ordinary piano, in no way interferes with the manual operative mechanism associated therewith.

As is clearly shown in Figs. 1 and 5, the air motor 130, is firmly mounted upon the roller box 51. The construction of this air motor is clearly set forth in the patent to A. F. Larson, No. 768,053, August 23, 1904, and a detailed description is unnecessary here. We provide, however, novel means whereby this motor may be regulated when applied to automatic playing pianos as described herein. This air motor is operated entirely by suction, and we provide means whereby this suction is created at 131 and 132, where we have illustrated the first and second motor bellows respectively. The first motor bellows, 131, is connected with the air regulating chamber 41 by way of passage way 133, and is also connected with the second motor bellows 132 by way of the passage 134. The second motor bellows, 132, is connected with the air motor by way of the passage way, 135, in the block, 135', and the tube, 136, as is clearly shown in Figs. 1, 7 and 9. The first and second motor bellows are similarly constructed. In the interior of the motor bellows we provide a spring, 137, which is adapted to normally hold the motor bellows in a distended position. In the first motor bellows 131 this spring is comparatively stiff and strong while in the second motor bellows we provide a comparatively weak spring. The purpose of this will be hereinafter made apparent. The spring 137 is secured to the foundation board 8 by means of the screw, 138, and its tension may be adjusted by means of the screw, 139, in the manner apparent from the drawing. At its other end the spring is provided with the block, 140, to which is glued the strip, 141, of felt or similar material. A square link 142 formed of wire is pivoted in a slot, 142', in the block 140 and is held in place by the spring. The free side of the square link 55 engages the cover, 143. It is now apparent that when the bellows collapse the block 141 will be disposed over the opening 134 and it is evident that with this construction as just described there will be no friction or undue wear and tear of the parts while the bellows are in motion. We prefer to make the cover 143 removable so that access may be gained to the interior so that the various parts may be adjusted. It must be understood, of course, that in the first motor bellows 131

the valve 140 regulates the opening 133, while in the second motor bellows the valve 140 regulates the opening 134.

When the exhaust feeders are in operation air is exhausted from the motive device 70 through the first and second motor bellows. The second motor bellows 132 having the weaker spring, as before stated, readily responds to the normal pressure exerted by the feeders. This bellows, precisely as has been 75 described with reference to the main bellows, acts as a reservoir and maintains a constant and steady exhaust through the air motor. The mode of this regulation will readily appear from an examination of Fig. 7 where it 80 is evident the valve block 140 will tend to close the passageway 134 when the exhaust feeders are in operation, this tendency being directly proportionate to the strength of the exhaust. Thus when the exhaust is increased 85 the block 140 will tend to bear more strongly over the passageway 134 and because of the layer of felt 141 the passageway 134 will be proportionately restricted. The amount of air, therefore, exhausted from the 90 motive device remains constant and steady and any tendency for jerky or sudden action, due to the alternate operation of the exhaust feeders, is entirely overcome. Should the feeders be forced; however, the first motor 95 bellows 131 will operate, the tendency for this stronger spring to distend its bellows being overcome by the increased exhaust pressure. As before stated, the motor bellows 131 is constructed similar to the bellows 100 132, and when the exhaust is increased the passageway 133 will be restricted by its valve precisely in the same manner as has been described with reference to the restriction of the passageway 134 by the valve 140. When 105 the exhaust is thus increased the valve of the first motor bellows 131 will tend to restrict the passageway 133, thereby primarily diminishing the flow of air, and the valve of the motor bellows 132, being controlled by the 110 weaker spring, will regulate the passageway 134 so as to maintain a constant and steady exhaust through the motor. Thus the speed of the motor is always the same after it has been adjusted to the desired degree, no matter what be the power applied to the power bellows. 115

Since it is desired to rewind the note sheet; that is, return it to its spool very much more rapidly than it is unwound we provide means 120 whereby this may be accomplished. A tube, 144, leads from the motor to the air chamber 41; and when it is desired to rewind the note sheet the direction of the motor is changed as will be hereinafter described and the regulating mechanism is so disposed that air is withdrawn from the motor through the conductor 144 in a comparatively large quantity by means of the direct connection between the motor and the chamber 41, the air in this case 125 130

being exhausted directly through the main bellows and not through the motor bellows as is the case when the conductor 136 is employed. Since the main bellows is of so much greater power than the motor bellows the speed of the motor is therefore proportionately increased. At the same time that the conductor 144 is substituted for the conductor 136 and the main bellows for the motor bellows, and the direction of the motor changed, the passage 47 is closed, as will be hereinafter described; this operation, of course, cutting off all communication between the action chamber and the bellows mechanism. This is desirable so that the playing mechanism will not operate while the note sheet is being rewound. We provide means whereby all these changes and substitutions are obtained by a single movement.

Referring now more particularly to Figs. 1, 13, 19 and 20, we have shown a construction wherein these different operations are accomplished. Mounted in the blocks, 145 and 146, is the rotatable shaft, 147, which is provided with the crank arms, 148, 149 and 150. To the lever arm 148 is pivoted the connecting rod, 151, which is fastened to the sliding rod, 152, by means of the connecting piece, 153 extending through the slot, 154 in the supporting board, 155. The rod 152 connects with the sliding valve, 156, which slides in the valve box, 157. Of course it is apparent that any rotation of the shaft 147 will facilitate a lateral movement of the sliding valve, 156, in the valve box, 157. The tube 136 is connected with the valve box by way of the channel, 158. The opening, 159, leads to the operating parts of the motor which is of such construction that its speed will be governed by the amount of air passing from the opening 159 to the opening 158. The slot 158 is made long and narrow so that the flow of air may be easily regulated and it is apparent that any movement of the sliding valve will either increase or decrease the flow of air through the valve box. Mechanism will hereinafter be described whereby the operator of the instrument is enabled to control the movement of this sliding valve. In the valve box is also provided the opening, 160, which is normally closed by the sliding valve 156. In the sliding valve is provided the opening, 161, which is so situated with regard to the opening 160 and the position of the sliding valve in the valve box that when the valve is moved to the extreme left, thereby closing the opening 158, the opening 160 will register with the opening 161. This opening 160 leads to the tube 144 which, as before mentioned, leads to the air chamber 41. When the openings 160 and 161 register a comparatively large passage way is formed and a great quantity of air is thereby admitted to flow through the valve box. Since at this time,

as has been before described, the main bellows is substituted for the motor bellows a very much stronger suction is created to operate the air motor which, consequently, greatly increases the speed thereof. In order that the direction of the motor may be changed at this point, we provide upon the sliding rod 152 the extensions or arms, 162 and 163, which may be securely fastened thereto, but are adjustable. Riding in the blocks, 164, 164, is the bar, 165, which governs at 166 the clutch mechanism. Upon the shaft, 167, we provide a loose gear (not shown) which, when brought into action transmits motion to the roller 55, and we also provide upon this shaft a loose sprocket 168, which by suitable chain mechanism is connected with the sprocket 169 on the spool shaft, 170. The clutch mechanism 166 serves to bring the loose sprocket and loose gear into rigid connection with the shaft 167 alternately according to the motion of the governing rod 165. The connection between the governing rod 165 and the clutch mechanism 166 is such that when the rod is in its right-hand position the clutch will cause the motion of the shaft to be transmitted by way of the loose gear to the roller 55, facilitating motion in the direction of the arrow, 172. When the rod 165 is in its left-hand position the clutch is thrown into engagement with the loose sprocket and the shaft 165 transmits motion to the spool shaft, 170, in the direction of the arrow, 173. In order that this shaft 165 may be thrown from left to right, or vice versa, in a proper manner, we provide the adjustable extension, 174, secured to said shaft. This arm 174 extends between the downwardly extending arms, 162 and 163, so that a predetermined motion may be given thereto by the proper movement of the shaft 152 upon which the extensions 162 and 163 are mounted. As before stated, it is essential that the motor clutches be reversed simultaneously with the sudden increase of air flowing through the valve box, and in order to secure this result we mount the extension 162 upon the shaft 152 in such a manner that as the opening 160 registers with the opening 161 the extension 162 will engage the arm 174 and move it a predetermined distance to the left. This movement, as hereinbefore stated, secures the rotation of the spool 54 in the direction of the arrow 173. It is now apparent that the note sheet may be rewound at the proper time very rapidly.

When the note sheet is applied and it is desired to play the instrument the operator will, by means of a mechanism hereinafter to be described, revolve the shaft 147 so that the sliding valve 156 will be drawn toward the right, thereby closing the passage 160 and opening the passage 158. The arm 163 is so disposed upon the shaft 152 that while

this movement is taking place it will engage the arm 174 whereby the same will be moved to the right a predetermined distance; this movement causing, as before stated, a resetting of the clutch, which throws out of engagement with the shaft 167, the sprocket 168 and simultaneously connects with spool 55 to cause rotation thereof in the direction of the arrow 172.

10 Referring now more particularly to Figs. 13, 19 and 20, we have shown the means whereby the operator of the instrument is able to revolve the shaft 147 so as to secure the different effects and results, as has been heretofore described. Pivoted at 175 to the under side of the supporting wall 1 is a lever, 176, to which is rigidly secured the link, 177. The bar, 178, is pivoted at one end to the link, 177, at 179, and at its other end it is pivoted at 180 to the lever arm 150, secured to the shaft 147. Riding in the blocks, 181, 181, secured to the under side of the wall 1 is the sliding bar, 182, to which is pivoted at 181' the link, 182', which, in turn, is pivoted at 185 to the lever 176. To the bar, 182, is secured the adjustable extension, 183, which is provided with the finger piece, 184, extending through the slot 185' to the wall 1, and the slot, 186, in the key strip 30 121, where it may be manipulated by the operator of the instrument. It will be seen by a careful consideration of the lever mechanism just described that a lateral movement of this finger piece 184 will facilitate any desired rotation of the shaft 147, and it is evident that the different effects described as resulting from the rotation of the shaft 147 may be obtained by the proper manipulation of the finger piece 184. The lever 176 is 40 also extended past the fulcrum 175 so that it may be pivoted at 187 to the rod, 188, which rides in the blocks, 189, 189, secured to the under side of the wall 1. The other end of the rod 188 is bent upwards as shown 45 at 190 in Fig. 20 and serves to operate the valve mechanism in the air chamber, as will be presently described. In the walls 88 and 89 of the air chest 6, is pivoted the rod, 191, provided at its outer end with the crank, 50 192. Within the chamber 46' is adjustably mounted upon the shaft, 191, the arm or extension, 193, which engages, as is clearly shown in Fig. 12, the pin, 194, on the valve block 48. It is now apparent that any rotation 55 of the shaft 191 in the direction of the arrow, 195, will cause the valve 48 to be forced downward to close the passage 47, by reason of the engagement by the extension 193 with the pin 194 against the tension of the spring 49. It is, of course, clear that all 60 air exhausted from the action of the playing mechanism must pass through this opening 47. Since it is necessary that the piano mechanism remain inactive during the time 65 while the note sheet is being rewound, we

provide means whereby this valve is closed automatically, at the time that the motor clutches are reversed for the rewinding of the note sheet. This desirable result is secured by reason of the engagement of the end 190 70 of the rod 182 with the crank 192 on this valve shaft 191. It is apparent from Fig. 20 that when the bar 82 is moved toward the left the end 190 will engage crank 192, and, by reason of its particular formation, will 75 force downwardly the crank 192; that is, will rotate the shaft 191 in the direction of the arrow 195. As has heretofore been stated, such a rotation will cause the valve 48 to close the passage 47, thereby cutting 80 off all communication between the playing mechanism and the suction apparatus.

To the arm or extension 149 which is secured to the shaft 147 is pivoted at 196 the rod, 197, which is provided at its other end 85 with the pointer, 198, extending through the slot 199 in the front board, 200, and being arranged so that it may pass over the scale, 201, which is in view of the operator of the instrument. It is apparent, of course, that 90 any movement of the finger piece 184 will be communicated to the pointer 198, by reason of the lever action with the shaft 147, as has been described. The scale 201 may be provided with the indicating marks, 202, 95 202, which may indicate the different speeds of the motor and the mark, 203, which indicates the position in which the pointer must be to rewind the note sheet. This speed scale is desirable so that the operator can 100 follow with reference thereto any directions which may appear upon the note sheet. From the description of the various parts associated with the shaft 147, it has been made clear that several regulations and 105 adjustments are made by a single movement of the finger piece 184. A movement of the finger piece 184 to the extreme left secures the following effects: The air motor clutches are reversed; the motor valve is adjusted so 110 that a comparatively large amount of air may be passed therethrough; the main bellows is substituted for the motor bellows, thereby greatly increasing the suction from the air motor; the valve 48 is closed, cutting 115 off communication with the action, and the pointer 198 registers with the indicating mark 203. From this description it may readily be seen what effect any other movement of the finger piece 184 may have upon 120 the various associated parts.

Referring now to Figs. 1 and 23, we have shown means whereby the note sheet may be adjusted so as to travel properly and accurately over the tracker-board. The spool 54 is mounted, as is plainly shown in Fig. 1, in the spool shaft 170, which is adapted to be rotated, as has heretofore been described, by reason of connection with the motor shaft of the sprocket 169. The spool shaft, 170, is 130

rotatably mounted in the bearing, 204, in the roller-box, 51, the other bearing, 205, being also mounted in the roller-box. This is a spring bearing which admits of the insertion and which secures a proper connection with the spool stud, 206. In order that this spool may be moved laterally, we provide the means shown in Fig. 23. Mounted upon the shaft 171 is the sleeve 207, provided with the rim, 208, and the groove, 209. Pivoted at 210 in the brace, 211, is the adjusting lever, 212, the upper end of which is bifurcated so as to properly engage the groove 209 in the sleeve. The top of this end is provided with the rounded head, 213, so as to reduce to a minimum the friction caused by this engagement with the sides of the groove during the revolution of the shaft. The lower arm, 214, of the adjusting lever is also provided with a rounded head which bears in the traveling block, 215, which has threaded engagement with the thumb screw, 216. A collar, 217, prevents lateral movement of the thumb screw 216 in the bearings, 218, which is mounted in the roller-box, 51. The traveling block 215 is provided with the bifurcated end, 219, which engages the pin, 220, mounted in the front plate of the bearing 218. It is now evident that any manual rotation of the thumb screw by means of the head, 221, which is accessible by the operator, will cause the block 215 to travel laterally, any rotation of the same being impossible on account of its engagement with the pin 220. An adjustable collar, 222, may be provided to prescribe the limit of movement of the traveling block. It is evident now that any rotation of the head 221 of the thumb screw will cause a lateral movement of the traveling block 215 which will, by virtue of the lever 212, move the spool shaft, 170 in the desired direction against or with the tension of the spring, 223, in the bearing 205, so that the note sheet will always be maintained in proper position while crossing the tracker-board. We provide the spring, 224, fastened by the screw, 224', and made adjustable by the screw, 225, bearing upon the rim 208 of the sleeve 207 which forms a drag thereon, thereby keeping the end sheet taut while it passes from the spool to the take-up roll. We have shown a form of joint which we have found it convenient to employ in making pivotal connection between bars or levers. This improved construction is illustrated in Fig. 21 and at *x* we have shown the end of one bar or rod, and at *y* the end of another. The bar *y* is provided with the tapered pin *w* which engages the tapered opening *z* in the rod *x*. On the rod *y* is securely fastened the spring *s* provided with a comparatively large opening, *o*, and so disposed that it may exert downward pressure upon the bar *x*, the pin *w* extending through the opening *o*. It is a feature of this arrange-

ment that there is always a solid and positive connection between the two bars. Any instability is taken up by the taper of the opening *z* and the pin *w*, on account of the downward pressure of the spring *s*. It is evident that this form of connection is noiseless and efficient and is of simple and economical construction. Although we have not shown all of these pivotal joints which occur in the various portions of the construction in detail as being of this arrangement, we wish it to be assumed that they are all of this construction. 70 75

It is a feature of our invention that the parts may be easily removed, repaired and adjusted. 80

Referring now to Fig. 3, we have shown a construction which admits of this easy assemblage and disassemblage. The valve and primary pneumatic rack is separable from the bellows rack and channel port at 226 and 227, and is held in place by a plurality of screws which may easily be removed so as to facilitate the removal of the valve and pneumatic rack so as to make adjustment and repairs. The top board, 228, is also removable so that adjustment may be made of the parts under it. The screws 68 are so situated that they may be easily reached and adjusted. 95

Referring now to Fig. 25, we have shown a modification within the scope of our invention and which is a convenient form of construction on account of its specific arrangement which admits of ready access to those parts upon which adjustment is required. The modification lies in the different disposition of the valve and primary pneumatic rack, the construction being such that the valve stem lies horizontal instead of vertical as shown in Fig. 3. The front board, 229, is provided with the ports, 230, to admit the outside atmosphere to the chamber 231. This board 229 is made easily removable so that access may be readily had to the adjusting screws 68 which are in full view and in such position that they may be readily reached. It must be remembered in considering this modification that while the note sheet governs the opening 53 in the tracker-board the air is constantly being exhausted from the channels 54', 55', and the primary pneumatic chamber 58, by way of the small passage way 68, as has been described heretofore with reference to Fig. 3. On account of the small capacity of the channels and passages just named, the pressure therein is very low, there being nearly a vacuum. The air, of course, is being exhausted from the action chamber 50 but on account of its large capacity and the frequent admissions of air therein the pressure therein is considerably higher than that in the primary pneumatic chamber 58. With these conditions, it is, of course, manifest that the leather washer 110 115 120 125 130

59 will normally be in position shown in Fig. 25, thus holding the valve 60 in such a position as to close communication between the action chamber and the associated action bellows. This feature, of course, is necessary for the proper operation of the playing mechanism. It is manifest that the valve and primary pneumatic rack is separable from the bellows rack and channel board at 10 232, which is a desirable form of construction, so as to admit of convenient adjustment and repair.

In Fig. 26 we have shown the application of the end block, 233, which is provided with 15 the channel, 234, registering when in place, with the action chamber 50. The block 233 is separable from the side piece 3 at 235, and may be held in place by the screws, 236, in such a manner, of course, that the channel 20 234 will register with the channel 5 in the side piece 3. An end block of practically this construction is, of course, employed in the arrangement shown in Fig. 3.

Referring now to Fig. 27, it will be seen 25 that our invention is of such arrangement and construction that when the automatic playing mechanism is not in use the parts may be easily placed so as to be hidden from view, thus securing a piano of ordinary appearance. We provide in the upper front panel, 237, the sliding door, 238, which is disposed directly in front of the roller box 51. It is evident, of course, that this door may be 30 slid aside in any convenient manner so as to disclose the roller box when it is desired to employ the automatic playing mechanism. The treadle mechanism, of course, may be drawn forth and connected as has been hereinbefore described.

40 It is one of the important features of our invention that the parts are so arranged and disposed that the piano may be of ordinary size, changed neither in dimension or design or outside appearance. Another feature of 45 this invention is the convenient means for regulating the sound of the instrument, and also the speed, there being a minority of finger pieces for manipulation by the operator and the entire regulation and adjustment 50 being secured by simple and positive movements. The construction of all the parts is such that all the movements will be positive and noiseless, and it is evident from what has been described hereinbefore that all parts 55 which may require adjustment or repair are easily accessible and easily manipulated. Parts are so disposed and arranged that there will be a minimum of wear and tear upon the parts, and no unnecessary friction. The 60 construction is such that the entire mechanism is compact and uniform and of simple design. The construction is such that the operator may easily manipulate the regulating devices and need not exert an excess of 65 power upon the treadles, and the parts are

such that they cannot easily get out of order, provision being made for inexperienced operators who may force the operation or misuse the parts.

It is evident that changes and modifications, within the spirit and scope of our invention, could be made by those skilled in the art, and we do not wish to be limited, therefore, to the precise construction herein shown.

What we claim as new and desire to secure by Letters Patent is:

1. In an automatic playing piano, the combination of a piano frame, striking mechanism mounted upon one of the horizontal walls of said frame, a pneumatic action for association with the striking mechanism of the piano, a roller box mounted upon said pneumatic action, a tracker-board in said roller box, an air chest secured to the under side of said horizontal wall, said air chest having a partition wall, said air chest being divided into two chambers, one of said chambers being connected with the pneumatic action by way of openings in the horizontal wall and communicating with said other chambers by way of an opening through the partition wall, a valve for controlling said passageway, a supporting board extending downwardly from said chest, a pair of feeders disposed upon the rear side of said board, treadle mechanism for operating said feeders, said feeders communicating with said air regulating chambers by way of channels in said supporting board, a normally distended main bellows and an auxiliary bellows disposed at the front of the board and communicating with the air chamber, a valve for each of the channels leading from said chamber to said bellows, and means whereby the channel leading to said main bellows may be closed when the channel leading to said auxiliary bellows is opened.

2. In an automatic playing piano, the combination with a piano frame, of striking mechanism mounted upon one of the horizontal walls thereof, a pneumatic action for association with the piano striking mechanism, an air chest secured to the under side of said horizontal wall, a partition wall in said chest dividing the same into two chambers, one of said chambers communicating with the pneumatic action by way of channels through the horizontal wall, a port between said chambers, a valve controlling said port, a supporting board extending downwardly from said chest, a pair of feeders mounted upon the rear side of said board and communicating directly with one of the chambers of the air chest, a main exhaust bellows mounted upon the front side of the board and connected with said chest, and auxiliary bellows similarly mounted and connected with the chest, valves controlling the channels leading into the main and auxiliary bellows, and lever mechanism whereby the valve governing

the channel leading into the main bellows may be closed when the valve governing the channel leading into the auxiliary bellows is opened.

5. 3. In an automatic playing piano, the combination of a piano frame, striking mechanism mounted upon one of the horizontal walls thereof, a pneumatic action mounted upon said wall and associated with the striking mechanism of the piano, a roller box supported upon said pneumatic action, a tracker-board normally connected with the pneumatic action, a motor secured to the roller box, a spool and take-up roll in said box adapted to be operated by said motor, an air chest secured to the under side of said horizontal wall, said chest being divided into two compartments, a conducting compartment and a valve compartment, a supporting board extending downwardly from said air chest, a pair of feeders disposed upon the rear side of said board and connected directly with said valve compartment by way of a channel in said supporting board, a main and an auxiliary exhaust bellows disposed upon the front of said board and connected with said valve chamber, a valve controlling the parts leading into the respective bellows, means whereby the valve controlling the channel leading into the main bellows may be closed simultaneously with the opening of the valve controlling the channel leading into the auxiliary bellows, motor bellows disposed upon the front of the board and connected directly with the valve chamber, an air conductor connecting the motor with the motor bellows, a port connecting said conducting and said valve compartments and a valve controlling said port.
- 40 4. In an automatic playing piano, the combination with a piano frame, of a pneumatic action mounted upon one of the horizontal walls thereof, a roller box mounted upon said pneumatic action, a motor secured to said roller box, a spool and take-up roll in said box adapted to be operated by said motor, an air chest secured to the lower side of said horizontal wall, a partition wall in said chest dividing the same into a conducting compartment and a valve compartment, said conducting compartment being connected with the pneumatic action by way of channels in said horizontal wall, a port connecting said conducting and valve chambers, a valve controlling said port, means for creating an exhaust pressure in said valve chamber, motor regulating bellows for regulating the exhaust through said motor, means for connecting said motor directly with said valve compartment, and means whereby the valve governing said port may be closed and the path from the motor to the valve compartment be opened simultaneously.
- 65 5. In an automatic playing piano, the combination with a piano frame, of striking mechanism mounted upon one of the horizontal walls thereof, a pneumatic action associated with the striking mechanism of the piano, an air chest, a dividing wall in said chest separating the same into a conducting chamber and a valve chamber, a supporting board secured to and extending downwardly from said chest, a pair of feeder bellows mounted upon the rear side of said board and communicating with said valve chamber by way of a channel in said board, treadle mechanism for operating said feeder bellows, suitable flap valves for said feeder bellows whereby an exhaust pressure may be created in said valve chamber, a main and an auxiliary bellows mounted upon the front of said supporting board and adapted to communicate with said valve chamber, valves controlling the connection between said main and auxiliary bellows and said valve chamber, and means whereby connection between said main bellows and said valve chamber is cut off when said auxiliary bellows is connected with said air chamber, said means being adapted to be manipulated by the operator at the front of the instrument.
6. In an automatic playing piano, the combination with a piano frame, of striking mechanism mounted upon one of the horizontal walls thereof, a pneumatic action associated with the striking mechanism of the piano, an air chest connected with said pneumatic action, a supporting board secured to and extending downwardly from said chest, a dividing wall within said chest separating the same into a conducting chamber and a valve chamber, feeder bellows mounted upon the rear side of said supporting board and connected with said valve chamber, operation of which creates an exhaust pressure in said valve chamber, a tracker-board connected with said pneumatic action, an air motive device for drawing a note sheet over said tracker-board, a motor regulating bellows connected directly with said valve chamber, a second motor regulating bellows connected with said first motor regulating bellows, an air conductor connecting said motive device and said second motor regulating bellows, a second air conductor connecting said motive device directly with said valve chamber, and valve means for substituting one of said air conductors for the other.
7. In an automatic playing piano, the combination with a piano frame, of a pneumatic action mounted upon one of the horizontal walls thereof, a roller box mounted upon said pneumatic action, a tracker-board in said roller box connected with said pneumatic action, an air chest secured to the under side of said horizontal wall, a partition wall in said chest dividing the same into a conducting chamber and a valve chamber, said conducting chamber connecting with

said pneumatic action by way of channels in said horizontal wall, a port connecting said conducting and valve chambers, a valve controlling said port, a supporting board secured to and extending downwardly from said chamber, a pair of feeder bellows mounted upon the rear side of said board and connected directly with said valve chamber, a main bellows and an auxiliary bellows mounted upon the front of said board, valve mechanism whereby said main and auxiliary bellows may be alternately brought into employment, a motor regulating bellows mounted upon the front of said supporting board and connected directly with said valve chamber, a second motor bellows connected with said first motor bellows, a distention spring for each motor bellows, said springs being of dif-

fering tension, an air motor mounted upon said roller box, an air conductor leading from said motor to said second motor bellows, a second air conductor leading from said motor directly to said valve chamber, valve mechanism for said air motor and lever mechanism for actuating said valve controlling said port in said partition and for actuating said air motor valve to substitute one of said air conductors for the other simultaneously.

In witness whereof, we hereunto subscribe our names this seven^{teenth} day of February 30 A. D., 1906.

AXEL F. LARSON.
